UNITED STATES PATENT OFFICE

147,416

DESIGN FOR SAFETY SHEARS

Edward A. O'Brien, Truro, Nova Scotia, Canada

Application May 7, 1946, Serial No. 129,410

Term of patent 14 years

(Cl. D22—5)

To all whom it may concern:

Be it known that I, Edward A. O'Brien, a citizen of the Dominion of Canada, residing at Truro, in the Province of Nova Scotia and Dominion of Canada, have invented a new, original, and ornamental Design for Safety Shears, of which the following is a specification, reference being had to the accompanying drawing, forming part thereof.

Figure 1 is a plan view of the safety shears showing my new design, and illustrating the same in open position.

Figure 2 is a plan view of the safety shears shown in Figure 1 but illustrating the same in closed position, and

Figure 3 is a cross-sectional view taken on the plane of the line 3—3 of Figure 1.

I claim:

The ornamental design for safety shears, as shown.

EDWARD A. O'BRIEN.
